UNITED STATES PATENT OFFICE.

WILLIAM ESTY, OF LACONIA, NEW HAMPSHIRE.

DESIGN FOR A SPRINKLER.

SPECIFICATION forming part of Design No. 26,253, dated November 10, 1896.

Application filed March 5, 1894. Serial No. 502,436. Term of patent 14 years.

To all whom it may concern:

Be it known that I, WILLIAM ESTY, a citizen of the United States, residing at Laconia, in the county of Belknap and State of New Hampshire, have invented and produced a new and original Design for Sprinklers, of which the following is a specification, reference being had therein to the accompanying drawings.

10. The invention consists in a design of simple, symmetrical, and pleasing character for the article of manufacture which is known as a "sprinkler."

In the accompanying drawings, Figures 1 and 2 respectively show my design, each point of view being taken so as to indicate clearly all of the features thereof.

The leading features of my design are as follows:

20. The upper or head portion 2 of the frame is cylindriform, and from the said cylindriform head portion 2, intermediate of the length thereof, spring oppositely-directed curved arms 1, which at first extend outwardly and then downwardly, the lower portions thereof converging toward each other, as shown clearly in Fig. 1, and merging into a somewhat-enlarged connecting portion. The figure described by the two arms is oviform, and the 25 meeting portions of the arms 1 nestle in the

upper central concavity of the crown-like disk or appendage 3, the requisite finish or apex to the oviform figure described by the arms 1 being furnished by a projection located below the said crown-shaped appendage 3, as shown 35 clearly in both of the figures of the drawings. A rounded disk-like head 5 constitutes a finish for the lower end of the said cylindriform head portion 2. The wing-like part 4 bridges by its inner end 6 the space between the 40 rounded head 5 and the central cone or dome 7, which extends upwardly from the enlarged connecting portion between the lower ends of the arms 1. This wing-like part 4 tapers uniformly along its upper and lower edges from 45 the points where it touches the said rounded head 5 and cone or dome 7, and the axis of the said wing-like part 4 is marked by a longitudinal rib or ridge.

Having thus described my design, what I 50 claim, and desire to secure by Letters Patent, is—

The design for a sprinkler, substantially as shown.

In testimony whereof I affix my signature 55 in presence of two witnesses.

WILLIAM ESTY.
